UNITED STATES PATENT OFFICE

157,853

SHOCK ABSORBER FOR BICYCLES

Charley T. Flanagan, Henderson, Tex.

Application April 15, 1948, Serial No. 145,747

Term of patent 14 years

(Cl. D90—11)

To all whom it may concern:

Be it known that I, Charley T. Flanagan, a citizen of the United States, residing at Henderson, county of Rusk, State of Texas, have invented a new, original, and ornamental Design for Shock Absorber for Bicycles, of which the following is a specification, reference being had to the accompanying drawings, forming a part thereof.

Figure 1 is a view in side elevation of a bicycle shock absorber showing my new design.

Figure 2 is a view in front elevation of the shock absorber.

Figure 3 is a fragmentary view in side elevation of one of the limbs of the shock absorber looking from the right in Figure 1.

I claim:

The ornamental design for a shock absorber for bicycles, as shown.

CHARLEY T. FLANAGAN.
